[57] CLAIM

The ornamental design for a tray insert for tape cartridges and tape cassettes, substantially as shown and described.

DESCRIPTION

FIG. 1 is a top plan view of a tray insert for tape cartridges and tape cassettes, showing my new design;
FIG. 2 is a front elevational view thereof;
FIG. 3 is a right side elevational view thereof;
FIG. 4 is a bottom plan view thereof;
FIG. 5 is a enlarged scale fragmentary, cross-sectional view taken along line 5—5 of FIG. 1; and,
FIG. 6 is a enlarged scale fragmentary, cross-sectional view taken along line 6—6 of FIG. 1.
